(57) **CLAIM**

The ornamental design for an angled belt loop clip, as shown and described.

DESCRIPTION

FIG. 1 is a rear perspective view of the angled belt loop clip; FIG. 2 is a front perspective view of the angled belt loop clip;

FIG. 3 is a front elevational view of the angled belt loop clip;

FIG. 4 is a back elevational view of the angled belt loop clip;

FIG. 5 is a top plan view of the angled belt loop clip;

FIG. 6 is a bottom plan view of the angled belt loop clip;

FIG. 7 is a right side elevational view of the angled belt loop clip;

FIG. 8 is a left side elevational view of the angled belt loop clip; and,

FIG. 9 is a rear perspective view of the angled belt loop clip with a belt passing therethrough.

The dashed broken lines illustrating the belt are not part of the claimed design and form no part thereof.

1 Claim, 6 Drawing Sheets
